Primary Examiner — Ricky Pham*(74) Attorney, Agent, or Firm* — Wood, Herron & Evans, LLP(57) **CLAIM**

The ornamental design for a tool chest, as shown and described.

DESCRIPTION

FIG. 1 is a front isometric view of our new, original and ornamental design;

FIG. 2 is a front view thereof;

FIG. 3 is a right side view, the left side view being a mirror image thereof;

FIG. 4 is a top side view thereof; and,

FIG. 5 is a bottom side view thereof.

The unshown portion of the tool chest forms no part of the claimed design.
